CLAIM

The ornamental design for a translucent cup with measurement indicators, as shown and described.

DESCRIPTION

FIG. 1 is a front perspective view of a translucent cup, with shading showing translucency and white color showing transparency, showing our new design;

FIG. 2 is a back perspective view of the translucent cup of FIG. 1;

FIG. 3 is a front elevational view of the translucent cup of FIG. 1;

FIG. 4 is a back elevational view of the translucent cup of FIG. 1;

FIG. 5 is a left side view of the translucent cup of FIG. 1;

FIG. 6 is a right side view of the translucent cup of FIG. 1;

FIG. 7 is a top plan view of the translucent cup of FIG. 1;

FIG. 8 is a bottom plan view of the translucent cup of FIG. 1;

FIG. 9 is a cross-sectional view of the translucent cup alone the 9-9 line shown in FIG. 3; and,

FIG. 10 is a cross-sectional view of the translucent cup alone the 10-10 line shown in FIG. 7.

The broken lines depict environment, and the elements shown in broken lines form no part of the claimed design.
